ARNOLD H. TOLD, OF CHICAGO, ILLINOIS

WHEEL STOP

Application filed July 30, 1932. Serial No. 626,886.

The invention relates to devices applied to railway tracks at the end of a spur or siding to limit the movement of a car along the track.

The principal object of the present invention is to provide an effective device which is easily constructed and particularly one which is adapted to use material which all railway shops and yards and many maintenance crews and others will have available for this purpose.

Briefly the invention consists in utilizing short lengths of rails to form the wheel stop and the bracing structure whereby it is secured to the road bed.

15 In the accompanying drawing illustrating the invention—

Figure 1 is a side elevation of one form of the invention, showing it applied to the end of a traffic rail.

20 Figure 2 is a vertical transverse section on the line 2—2 of Figure 1.

Figure 3 is a side view of a modified form of structure.

25 Figure 4 is a side view of another form of the invention.

Figures 5 and 6 are transverse sections on the corresponding section lines of Figure 4.

Figure 7 is a side view of another form of the invention.

30 Figure 8 is a horizontal section taken on the line 8—8 of Figure 7.

The wheel stop element shown in Figures 1 and 2 consists of a length of rail 1, preferably corresponding in section to the traffic rail 2, and having its end 3 cut square to abut against the end of the traffic rail. Splice plates S secure the traffic rail and the wheel stop together. The rear portion of element 1 is bent upwardly preferably to the contour

35 of a car wheel and the entire section is braced longitudinally of the track by relatively shorter lengths 4 and 5 welded to the wheel stop element 1 at spaced points 6 and 7 and converging rearwardly to be secured to each

cured to the lower portion of rail 5 and are disposed to engage the vertical faces of cross ties 10. If desired, similar angle clips 11 may be secured to the horizontal portion of element 1 to similarly engage cross ties 12.

50 The parts 1, 4 and 5 are easily procured by utilizing any discarded rail and are easily assembled by welding together at the points indicated. These parts all lie in the same general vertical plane and the webs of the 55 three members provide substantial resistance to any deformation due to the impact of a car against the stop portion.

55 The horizontal portion of the main member 1, as well as its upwardly bent portion, 60 form a smooth extension of the traffic rail and eliminate any tendency to derail a car moved against the stop. The structure is free of any securing elements, such as bolts, clamping elements and other parts subject to 65 loss and resulting failure of the stop. There are no pivoted or pinned joints to loosen and reduce the rigidity of the device irrespective of its age and the extent of its use. By extending portions 1a and 5a beyond the adjacent ends of brace 4, suitable surfaces are 70 provided for weld abutments W which substantially increase resistance to relative movement of the parts of the device.

75 In the device shown in Figure 3, the horizontal rail section 13, which is arranged to abut the end of the traffic rail, is straight from end to end of the device. The wheel stop element 14 and the brace 15 therefor sit on top of section 13 and are welded thereto as indicated at 16 and 17 and to each other as indicated at 18. Suitable angle clips 19 are secured to the bottom flange of rail 13 and are disposed to engage successive cross ties 20.

80 As in the form previously described, the wheel stop element 14 forms in effect an upwardly inclined projection on the rail 13, having the same section, and providing a continuous rail head element for engagement 85 with the car wheel. The other advantages 90

45 other as by a weld at 8. Angle clips 9 are se-

referred to in connection with the construction shown in Figures 1 and 2 are inherent also in this form of the invention.

Figures 4, 5 and 6 illustrate rail sections 5 21, 22 and 23 corresponding to those shown in Figure 1 but these sections are held together by means of clips or gussets 24, 25 and 26 which are bent over the rail flanges and heads and are riveted to the rail webs. As in the 10 first form of the invention, the entire section of each rail 22 and 23 is utilized to abut the flange of the wheel stop rail 21 and the webs of all three rail lengths are united in a rigid structure.

15 Figures 7 and 8 illustrate another form of the invention in which the rail element 27 is used to abut the traffic rail (not shown) and to form the upwardly extending wheel stop engaging element which is here shown as 20 being straight instead of curved. The stop element is braced by a pair of triangular shaped plates 28 having recessed portions 29 shaped to receive the flange 30 of the wheel stop element. Plates 28 are secured together 25 after being applied to the wheel stop rail.

It will be seen from the above and by reference to the drawing that the objects and advantages mentioned above are attained by each of the structures described in detail and 30 it will be obvious to those skilled in the art that other modifications may be made without departing from the spirit of the invention and the exclusive use of any form of the invention coming within the scope of the 35 claims is contemplated.

What is claimed is:

1. In a wheel stop, a section of a rail having a substantially horizontal portion, terminating at its forward end in a face adapted to 40 abut the end of a traffic rail, and having a rear part inclined upwardly of said horizontal portion to form a wheel engaging element, and a structure at the rear of said upwardly inclined part arranged to brace the 45 latter to road bed ties located beyond the end of the traffic rail, said bracing structure consisting of rail pieces corresponding in cross section to said wheel-engaging element and having their forward ends abutting spaced 50 points on the base flange of said element and secured thereto.

2. In a wheel stop, a section of a track rail having a substantially horizontal portion and having a part inclined rearwardly and upwardly from said portion to form a wheel-engaging element, and a structure at the rear of said part arranged to brace the latter to road bed ties located beyond said horizontal portion, said brace structure consisting of 55 lengths of rail of cross section corresponding to the cross section of the stop element and having their forward ends abutting spaced 60 points on the flange of the stop element and welded to the latter throughout the width 65 thereof.

3. A wheel stop constructed to be applied as a unit to the end of a traffic rail and including a length of horizontally disposed rail with its end cut vertically to abut the end of the traffic rail, another length of rail inclined 70 upwardly and rearwardly from and resting on top of said horizontal rail with its lower end bevelled to join the heads of the two rails so as to form a continuous member shaped to fit the contour of a car wheel, and means 75 securing the two rail elements to each other.

4. A device as specified in claim 3 which also includes a brace extending from the upper portion of said inclined rail to the rear portion of said horizontally disposed rail 80 and terminating in an end bevelled to overlie the top of said horizontally disposed rail and means securing said brace to the other elements of the device.

5. A wheel stop unit comprising a horizontal member, an upwardly and rearwardly inclined wheel engaging member sitting on top of said horizontal member, an upwardly and forwardly inclined brace member sitting on top of said horizontal member and connected 85 to the upper portion of said first mentioned inclined member, each of said members consisting of a piece of railroad rail and the webs of said members being disposed in a common vertical plane and the unit being 90 constructed to be applied to the end of a traffic rail to form a continuation thereof having an integral stop element.

6. A device as specified in claim 2 which includes a depending member on the horizontal 100 element for engaging the cross tie of the road bed.

7. A device as specified in claim 1 which includes a depending element on the rail section arranged to engage the vertical face of a 105 cross tie.

8. A device as specified in claim 3 which includes an angle having a leg secured to the flange of the horizontally disposed rail and a depending flange disposed to engage a vertical 110 face of a track cross tie.

9. A railway vehicle wheel stop comprising three pieces of car rail secured at their ends to each other in the form of a closed triangle, with one side disposed horizontally, 115 another side disposed to engage a vehicle wheel, and a third side forming a brace between the first mentioned sides, the webs of the rail pieces being located in the same vertical plane and the base flange of the brace 120 piece abutting the base flange of the wheel-engaging piece.

10. A stop as specified in claim 9 in which the horizontal side and wheel engaging side project beyond the ends of the bracing side, 125 there being shoulders formed on the first two mentioned rails engaging the ends of said brace rail.

11. In a wheel stop, a section of a track rail arranged to abut the end of a traffic rail and 130

extending upwardly and rearwardly therefrom, and a bracing structure at the rear of said section and extending downwardly and outwardly therefrom to engage track cross ties, said bracing structure abutting the base flange of said rail section throughout the width thereof to hold the same against twisting under impact forces.

5 In testimony whereof I hereunto affix my
10 signature this 26th day of July, 1932.
